AIR CONDITIONING SYSTEM

Peter Parke and Frank O. Marshall, Chicago, Ill.,
assignors to The Pullman Company, Chicago,
Ill., a corporation of Illinois

Application June 17, 1935, Serial No. 26,990

12 Claims. (Cl. 257—3)

The invention relates to a coordinated system of cooling, heating and ventilating for passenger carrying vehicles involving in the cooling phase the use of circulating ice water as a refrigerant 5 regulated by the increased water volume in the system resulting from the melting ice, whereby the waste of ice water by overflow is prevented and only the spent water drained.

The principal object of the invention is to 10 provide an air conditioning installation of low initial cost and of minimum weight and having relatively few parts so disposed as to require no change in the design of vehicles of present standard construction for the adaptation of the mechanism.

Another object of the invention is the provision of a refrigerating system that is positive 20 in action and practically foolproof in operation, having few moving parts, wherein the power requirements are reduced to a minimum and wherein the expenditure of motive power for refrigeration purposes is eliminated.

Another object of the invention is the provision of means for heating a vehicle from over- 25 head and using the same means of distribution of the air as used for cooling.

Another and important object of the invention is the provision of a combined heating, cooling or straight ventilating system with manually 30 controlled means for initiating the operation of one or the other as occasion demands.

The foregoing and other objects are achieved by the mechanism illustrated in the accompanying drawings, in which—

Fig. 1 is a diagrammatic view of a combined heating, cooling and ventilating system for vehicles constructed in accordance with this invention and illustrating the complete cooling cycle together with the system of heating and 40 the electric control circuits for thermostatically regulating both the cooling and heating systems;

Fig. 2 is a view in plan of a railway car utilizing a cooling system of the type exemplified in Fig. 1, portions being broken away better to 45 reveal the entire overhead installation;

Fig. 3 is a cross-sectional view taken on the line 3—3 of Fig. 2 showing the arrangement of the heating and cooling apparatus overhead and part of the mechanism beneath the car including means for draining the spent water from the system and the pump for circulating cooling water, together with means for removing impurities from the water; and

Fig. 4 is a similar view through only the lower

portion of the car looking towards the ice bunkers and sump tank of the cooling system.

Broadly speaking, the invention consists of a refrigerating system wherein cooled water is circulated by pumps beneath the car through surface coolers or coils located preferably at one end and concealed in the roof zone of the car, together with the air circulating blowers, filters and heating mechanism. Air is positively circulated in heat exchange relation with the coils, 10 whereby the air is cooled and dehumidified and distributed through suitable ducts to the passenger space.

In the drawings is shown a railway car 10 having the roof 11, ceiling 12 and transverse interior partitions 13 and 14, normally defining the passenger space. In addition to this main passenger space 15, there is provided a compartment 16 and toilet rooms 17 and 18, at opposite ends of the car—all of which are to be supplied with 20 conditioned air. All of the overhead air conditioning mechanism is located at one end of the car and a duct longitudinally of the car utilized for delivering the conditioned air to the passenger space. Above the toilet room 17 and extending 25 over the vestibule 19 and passageway 20 defined by partition 28 and side wall 29 and separated therefrom by ceiling 12, is a chamber 21 in which is mounted all of the overhead air conditioning equipment including filters 22 and 23, blowers 24, 30 driven by motor 27, cooling coils 25 and 26 and heating unit 28. All of this overhead equipment is contained within a smaller inner chamber 29 enclosed within the chamber 21 by roof 11 and side deck walls 30 and 31, but the entire 35 mechanism is rendered accessible for inspection and repair by suitable hatches 61 and 62 in the roof 11 and opening into the chamber 29, as best shown in Fig. 3. The inner chamber 29 is open only to the interior of the car and to the outside 40 atmosphere and closed to larger chamber 21. A duct 32 communicates at one end with this inner chamber 29 and extends longitudinally along the side deck wall 30 and is open to the passenger space 15, and compartment 16 through 45 the side deck wall 30, as at 33 and 34 respectively. Communication with toilet room 17 at one end of the car is obtained by means of a branch duct 35 opening through the ceiling 12 as at 36 and the washroom 18 at the opposite end is served 50 indirectly by means of opening 37.

The present invention contemplates an air conditioning system adapted for use in all seasons of the year. Provision is made for heating in the winter, cooling in summer and, if occasion de-

mands, the operation of the blowers alone as a straight ventilating system without benefit of heating or cooling.

Refrigeration is obtained by melting of ice in boxes 38 secured to the underside of car body 10 and preferably disposed upon opposite sides of the center sills 39 in position to be conveniently loaded with ice from the side of the car, as best shown in Fig. 4. The ice boxes are interconnected by means of pipe 48 forming, in effect, a single box and, obviously, a single box of sufficient capacity to carry the desired quantity of ice may be substituted for the two disposed as described, but the use of more than one is preferable in that the weight is better distributed upon the car. The water resulting from the melting ice drains into a sump tank 40 beneath the center sills through pipes 44 and is drawn by a centrifugal pump 42, driven by an electric motor 43, through a strainer 41 to remove the sediment and foreign matter that might enter the system when the ice boxes are being loaded. The strainer 41, pump 42 with its motor 43 and the overflow valve 51 are all mounted in an equipment box 54 mounted on the center sill 39 adjacent the ice boxes 38 and sump 40, as best shown in Fig. 3. The sump tank is provided with a breather 45 to permit the ice water to flow freely therethrough under suction of pump 42 and a drain plug 99 to permit the system to be drained when not in use.

From the sump, the water is pumped through pipe 46 to the cooling coil 25 in the roof zone of the car, thence to ice boxes 38 through pipe 48, to be sprayed over the ice at 49 and again delivered to the sump tank 40 for another similar cycle of operation. A portion of the return water from cooling coil 25 passes through pre-cooling coil 26 through pipe 47. The spent water from the precooler is conveyed by pipe 50 to an overflow valve 51 adjacent to the sump tank beneath the car and controlled by the volume of water therein where it is discharged from the system at 52 and drained to the ground. A breather 98 permits the free flowing of water through the overflow. This being the only means provided for removing excess water from the system, it will be seen that only the water from which the utmost work has been extracted will be overflowed. The overflow chamber 51 has fluid connection with the sump tank 40 by means of pipe 53 whereby the level of the water therein is the same as and directly controlled by the level of the water in the sump tank and the amount of water to be wasted determined by the meltage rate of the ice in boxes 38.

The meltage rate of the ice is automatically regulated by the amount of refrigeration necessary to the maintenance of an even temperature in the passenger space, such demand controlling the recirculation rate of the cooling water flowing over the ice by means of thermostatically controlled pump 42. A uniform temperature may thus be maintained in the passenger space regardless of the amount of ice in boxes 38, and any refrigerating tonnage demand automatically supplied by the ice meltage rate adjusting itself to the load requirements imposed—however they may vary.

As the cooling water circulates through the main cooling coil 25 and auxiliary cooling coil 26, fresh air from the outside is taken in over the vestibule 19 through opening 54 in the ceiling 12 and drawn into chamber 29 through filter 22, and coil 26 and forced through main coil

25. The cooled air is then recirculated through an opening 55 in ceiling 12 from the passageway 20 communicating directly with the passenger space, and passing thence over the cooling coil 25. A filter 23 is also placed directly over the recirculating air opening 55, as best shown in Figs. 2 and 3. The fresh air entering the chamber 29 through duct 56 first passes through pre-cooling coil 26, substantially reducing its temperature, thence through the main cooling coil 25 under pressure of blowers 24. The air is automatically dehumidified due to its heat exchange relation with the respective cooling coils, and, by its passage through the several coils, is rendered suitable for delivery to the passenger space. Drip pans, such as indicated at 57 in Fig. 3, are disposed beneath the cooling coils 25 and 26 to receive the water of condensation resulting from dehumidification of the air as it is passed over the coils.

The temperature of the water in precooling coil 26 will be somewhat higher than that prevailing in the main coil 25 as the water, before reaching the precooler, is first passed through the main cooler in heat exchange relation with the air passing therethrough into the passenger space, increasing the temperature of the water by the absorption of heat units from the air, but the temperature of the precooler will be sufficiently low substantially to reduce the temperature of the fresh air entering the mixing chamber 28.

The conditioned air, as it leaves the cooling coil 25 under pressure of the blowers 24, enters a plenum chamber 58 covered with insulation 100 and opening into the duct 32, and is divided into a plurality of air streams by the curved louvers 59 disposed within the duct 32 at the position where the air leaving the chamber 58 enters the duct to be distributed to the passenger space through openings 33. The compartment 16 is supplied with conditioned air from the duct through opening 34, and the toilet room 17, directly beneath the conditioning mechanism, is supplied through branch duct 35 at opening 36 in the ceiling 12 as best shown in Fig. 2. The duct 32 is disposed longitudinally of the car along one side deck wall 30 upon the lower deck roof 31a and is thoroughly insulated as at 60 to avoid the transfer of heat or cold between the air in the duct, the outside atmosphere, and car body. A duct of this type may readily be applied to existing cars without resorting to the expensive tearing-down and rebuilding incident to the application of interior ducts.

The blowers 24 maintain a static pressure within the car, creating seepages through door and window crevices sufficient to keep the air fresh by preventing the infiltration of dirt and dust that ordinarily occurs in vehicles not so equipped. These same blowers may be utilized to advantage at times other than when cooling is necessary. At such times as require neither cooling nor heating, the blowers may be used as a straight ventilating system whereby filtered fresh air at constant temperature is circulated throughout the car, and the infiltration of dirt and noise eliminated whereby the general comfort of the occupants of the vehicle is materially improved. The blowers 24 and motor 27 may be mounted on cushioning pads 101 and 102 if desired, as best shown in Fig. 3, to minimize vibration.

For the purpose of removing smoke from the interior of the car, an exhaust ventilator 83 is installed in the side deck wall 30 at the saloon 84 adjacent the toilet room 17 and communicat-

ing therewith by means of a grille 85 in partition 86 whereby smoke is withdrawn from the toilet room and from the car through the doorway 87 in side wall partition 88. The exhaust ventilator 83 communicates with the saloon 84 through the ceiling 12 by means of a short vertical duct 89.

The pump 42 and blowers 24 are operated by electric motors and no additional power will be required in the operation of the entire system other than is furnished by the regular car lighting generator 63, connected to rotating car axle 64 by belt 65, as best shown in Fig. 1. During car movement, the current from the generator 63 is fed through the switchboard and regulator panel 66 to the battery 67 by means of wires 68 and 69 and, subject to the control of relays 81 and 82 respectively as hereinafter described, is supplied to the motor 43 operating the pump 42 and to a solenoid 70, operating a steam control valve 71, through wires 72. The motor 27, operating the blowers 24 by means of a belt 73, is energized off the regulator panel 66 through wires 74 and is manually controlled by a multi-speed switch 75 installed in the circuit 74 and through suitable resistances 103 the blowers may be operated at different speeds as required. When the generator output ceases, the current stored in battery 67 will flow back through wires 69 and 72 to the pump motor 43 and solenoid valve 70 and to the regulator panel 66 and from there to the blower motor 27 through wires 74, as above described. The circuit 72 is tapped off wires 69 between the battery 67 and regulator panel 66 and a cutout switch 76 installed in the circuit whereby its energization may be manually controlled. The regulator panel 66 is preferably installed in the side wall 90 of the car in the passageway 20 as shown in Fig. 3.

The operation of the pump motor 43 and the solenoid valve 70 is normally controlled by thermostats 77 and 78, respectively, installed in the circuit 72 and responsive to changes in temperature in the passenger space. The respective ranges of temperature within which the thermostats are effective are regulated by the control switch 104 having the heat thermostat control portion 79 and cooling thermostat control 80 so interlocked as to preclude any possibility of heating and cooling occurring simultaneously. As shown the control switch 104 is in the off position at which time the blowers 24 may be operated without benefit of either heating or cooling. At the temperatures for which the respective thermostats may be set, the actuation of the respective relay 81 or 82 is thereby controlled to regulate either the operation of pump motor 43 or heat control valve 70 to supply the car with either heating or cooling depending upon the temperature requirements. In order that the cooled air may be delivered to the passenger space as quickly as possible at all times, the water pump 42 is so controlled that when the desired temperature is obtained as called for by the setting of thermostat 77, a resistance contained in relay 81 is cut in which reduces the pump speed to a point whereby only a small stream of water issues from the spray nozzles 48 so that cold water is always circulating through the system when cooling is required. In this manner uniform temperatures are maintained in the car as the air is cooled more quickly than if the water in the system became warm as it would be if the water pump 42 had been completely shut down.

The operation of blower motor 27 may similarly

be thermostatically controlled, whereby the volume of air delivered to the passenger space would be regulated as well as the temperature thereof, but, as shown, is manually controlled by the multi-speed switch 75. Current for standby service for the complete circuit is obtained from the battery 67.

Both the motor for operating the water circulating pump and that driving the blowers are of relatively small capacity and the amount of current consumed in their operation is practically negligible.

As best illustrated in Fig. 1, a heating element in the form of a radiator 28 is installed in the overhead chamber 29 adjacent the cooling unit 25 and in the path of the air entering the duct 32 for distribution to the passenger space, and heated by steam obtained from the main train line 91. When it becomes necessary to raise the temperature of the air in the car above that prevailing outside, the control switch 104 is placed in contact with the heat thermostat control portion 79 whereby the refrigerating system is automatically stopped by thermostat 77 and steam automatically admitted to the heating coil 28 by valve 71, actuated by solenoid 70 which is energized upon the action of relay 82 controlled by heating thermostat 78 in the passenger space. The heating system is of the vapor type operating substantially at atmospheric pressure. The high pressure steam from trainline 91 enters the vapor regulator 92 through pipe 93 and is reduced to atmospheric pressure and delivered through pipe 94 to the control valve 71 from which it is admitted to the heating coil 28 through pipe 95 under control of thermostat 78. As the vapor enters the heating coil 28, it is cooled and partially condensed by heat exchange action with the air passing over the coil into the passenger space and conveyed back to the control valve 71 through return pipe 96, thence through pipe 97 to the vapor regulator 92 again, where the water of condensation is drained from the system.

The blowers 24 are maintained in operation and fresh and recirculating air filtered and drawn into the chamber 29, and gathered into the blowers 24 and forced through the heating coil 28 under pressure of the blowers into the duct 32 and the passenger space the same as when cooling.

From the foregoing, it will be apparent that the complete installation is simple, economical, and automatic in operation with relatively few moving parts. It will readily be seen that the temperature and relative humidity within the car may be accurately regulated by the thermostatically controlled motors driving the water circulating pump and/or blowers and the thermostatically controlled heating system.

What we claim is:

1. In a vehicle air conditioning system comprising mechanism driven by a rotating car axle and including a pump for continuously circulating a refrigerant during the cooling operation, means for circulating air in heat exchange relation with said refrigerant, a plurality of coils in said refrigerant circuit, a cooling chamber, a fresh air inlet to said chamber delivering air for precooling by one of said coils, an inlet to said chamber for recirculating air from the car interior for cooling with said precooled air by another of said coils, air heating means, and thermostatically controlled relays for regulating said cooling or heating means according to temperature requirements.

2. In a vehicle air conditioning system comprising mechanism driven by a rotating car truck

axle and including a pump for continuously circulating a refrigerant during the cooling operation, means for circulating air in heat exchange relation with said refrigerant, an ice box beneath the vehicle, a cooling chamber in the deck zone of the vehicle, refrigerant circulation connections between said box and chamber, a plurality of cooling coils in said refrigerant circuit, air heating means, a heat control circuit controlling said heating means, a thermostat controlling said refrigerant circulating means, and relay means for opening said heat control circuit when the refrigerant circuit is energized.

3. In a vehicle air conditioning system comprising a cooling chamber in the deck zone of the vehicle, an ice box beneath the vehicle, a tank for receiving refrigerant from said box, refrigerant circulation connections providing continuous refrigerant flow between said tank and cooling chamber during the cooling operation, a plurality of cooling coils in said refrigerant circuit, means controlled by volume of refrigerant in the system for regulating the meltage rate of the ice in said box, means for circulating air in heat exchange relation with said coils, air heating means, a heat control circuit controlling said heating means, a thermostat controlling said refrigerant circuit, and relay means for opening said heat control circuit when the refrigerant circuit is energized and closing said circuit when the cooling mechanism is not in operation.

4. In a vehicle air conditioning system having a cooling chamber in the deck zone of the vehicle, an ice box beneath the vehicle, a tank for receiving refrigerant from said ice box, continuous refrigerant flow connections for use only during the cooling phase and including a plurality of cooling coils between said tank and chamber, a fresh air inlet to said chamber delivering air to said chamber for precooling by one of said coils, an inlet to said chamber for recirculating air from the car interior with fresh air for cooling by another of said coils, means for circulating air thru said inlets, air heating means, means controlled by the volume of refrigerant in the system for regulating the meltage rate of the ice in the box in accordance with refrigerant demand, a heat control circuit controlling said heating means, and relay means for opening said heat control circuit when the refrigerant circuit is energized and closing said circuit when the cooling mechanism is not in operation.

5. A vehicle having a passenger space to be supplied with conditioned air, air circulating mechanism located at one end of the car and above the passenger space, a cooling chamber enclosing said mechanism having fresh and recirculating air inlets and an outlet to the passenger space, an ice box beneath the vehicle, a tank for receiving refrigerant from said box, refrigerant circulation connections including a motor driven pump between said tank and chamber, a plurality of coils in said refrigerant circuit adapted one for precooling the fresh air and one for cooling the recirculated and fresh air, air heating means adjacent said mechanism and last mentioned coil, a plenum chamber for receiving the conditioned air for distribution to the passenger space, means for draining the spent water from the precooling coil, means controlling the pump speed upon a predetermined thermostatic setting, means for manually adjusting said pump control means, a heat control circuit controlling said heating means, and relay means for opening said heat control circuit when the refrigerant circuit is energized.

and closing said circuit when the cooling mechanism is not in operation.

6. A vehicle having a passenger space to be supplied with conditioned air, air circulating mechanism located at one end of the car and above the passenger space, a chamber accessible thru hatchway openings in the vehicle roof, a cooling chamber therein enclosing said mechanism having fresh and recirculating air inlets and an outlet to the passenger space, an ice box beneath the vehicle containing a water spray, a tank for receiving refrigerant from said box, refrigerant circulation connections including a motor driven pump between said tank and chamber, a plurality of coils in said refrigerant circuit adapted one for precooling the fresh air and one for cooling the recirculated and fresh air, air heating means adjacent said mechanism and last named coil, a plenum chamber for receiving the conditioned air for distribution to the passenger space, means for diverting the warmed water from the recirculated air cooling coil to the water spray for recirculation and to the precooling coil, means for draining spent water from said precooling coil, means for adjustably controlling the pump speed automatically upon a predetermined thermostatic setting, a heat control circuit controlling said heating means, and relay means for opening said heat control circuit when the refrigerant circuit is energized and closing said circuit when the cooling mechanism is not in operation.

7. In a vehicle air conditioning system comprising mechanism driven by a rotating car axle and including a generator, means including a pump for circulating a refrigerant, means for circulating air in heat exchange relation with said refrigerant, a cooling chamber above the passenger space enclosing said mechanism having fresh and recirculating air inlets and an outlet to the passenger space, an ice box beneath the vehicle and a tank for receiving refrigerant from said box, refrigerant circulation connections including a motor driven pump between said tank and chamber, a plurality of coils in said refrigerant circuit adapted one for precooling the fresh air and another for cooling the recirculated and fresh air, air heating means adjacent said mechanism and last mentioned coil, a plenum chamber and duct for receiving the conditioned air for distribution to the passenger space, means for draining the spent water from the precooling coil, manually controlled circuit means for initiating said heating, cooling and air circulating mechanism, control circuits for regulating said heating and cooling mechanism automatically upon a predetermined thermostatic setting, a heat control circuit controlling said heating means, and relay means for opening said heat control circuit when the refrigerant circuit is energized and closing said circuit when the cooling mechanism is not in operation.

8. In a vehicle ice-actuated air conditioning system including a pump for continuously circulating a refrigerant during the cooling operation, means for circulating air in heat exchange relation with said refrigerant, a plurality of coils in said refrigerant circuit, a cooling chamber, a fresh air inlet to said chamber delivering air for precooling by one of said coils, an inlet to said chamber for recirculating air from the car interior for cooling with said precooled air by another of said coils, and overflow mechanism for draining spent water from said precooling coil.

9. Air conditioning apparatus for a passenger vehicle, comprising a conditioning compartment

located in the roof zone of the vehicle, means for drawing in fresh and recirculated air and passing it thru said compartment, air cooling means in said compartment, an ice chamber for providing cold water thru the melting of ice, means for circulating the cold water to said air cooling means and returning a portion of same to said chamber, a pre-cooling coil mounted in said compartment in the path of at least some of the air to be cooled, and means for continuously passing the remaining portion of the water leaving said air cooling means thru said pre-cooling coil and then discharging it from said vehicle.

10. Air conditioning apparatus for a passenger vehicle, comprising a conditioning compartment, means for drawing in fresh and recirculated air and passing it through said compartment, air cooling means in said compartment, an ice chamber for providing cold water through the melting 15 of ice, means for circulating the cold water to said air cooling means and returning a portion of same to said chamber, a precooling coil mounted in said compartment for initially cooling the fresh air stream only, and means for continuously passing the remaining portion of the water leaving said air cooling means through said precooling coil and then discharging it from said vehicle.

11. An air conditioning system device of the class described, comprising in combination, an ice 20 container having a sump, a cabinet having means to recirculate air therethrough, a cooling coil in said cabinet positioned in the air path, means for continuously forcing water from said sump

through said cooling coil when the system is set for car-cooling and discharging it over the ice in said container, a pre-cooling coil having an outside air inlet and means whereby a predetermined portion of water passing from said cooling coil 25 may be caused to pass through said pre-cooling coil, means whereby the recirculated air and pre-cooled fresh air are mixed before reaching said cooling coil, overflow means operatively connected to the outlet of said pre-cooling coil whereby the drain off of surplus water will be direct therefrom.

12. A device of the class described comprising in combination, a refrigeration system including an ice container having a sump, a chamber having means to recirculate air therethrough, cooling means in said chamber positioned in the air path, means for continuously forcing water from said sump through said cooling means and discharging it over the ice in said container when the system is set for car cooling even though car cooling is not actually required, pre-cooling means having an outside air inlet and means whereby a portion of water passing from the sump 30 may be caused to pass through said pre-cooling means, means whereby the recirculated air and pre-cooled fresh air are mixed before reaching said cooling means, overflow means operatively connected to the outlet of said pre-cooling means whereby the drain-off of surplus water will be direct therefrom.

PETER PARKE.
FRANK O. MARSHALL.
